UNITED STATES PATENT OFFICE.

ALBERT SCHMIDT, OF FLINT, MICHIGAN, ASSIGNOR TO CHAMPION IGNITION COMPANY, OF FLINT, MICHIGAN, A CORPORATION OF MICHIGAN.

SPARK-PLUG AND METHOD OF FORMING THE SAME.

1,174,618.

Specification of Letters Patent.

Patented Mar. 7, 1916.

Application filed August 21, 1913. Serial No. 786,001.

To all whom it may concern:

Be it known that I, ALBERT SCHMIDT, a citizen of the Republic of France, residing at Flint, in the county of Genesee and State 5 of Michigan, have invented certain new and useful Improvements in Spark-Plugs and Methods of Forming the Same, of which the following is a specification, reference being had therein to the accompanying 10 drawings.

The invention relates to spark plugs, and has for its object the simplification of the method of manufacture and reduction in cost of same.

15 In the present state of the art, it is usual to form spark plugs with an outer metallic casing having a hexagonal portion for engagement of a wrench and an integral threaded nipple of reduced diameter for 20 engagement with the aperture in the engine casing. It is also usual to provide a shoulder within the metallic casing, against which the insulator bears, and a threaded bushing between the insulator and the case for holding 25 the former to its seat upon said shoulder.

With my improved construction the threaded bushing may be entirely dispensed with by forming a threaded engagement between the nipple portion and the hexagonal portion of the casing. Furthermore, the 30 construction is one which may be manufactured by a different method, viz. one in which the hexagonal and nipple portions 35 are cut from separate pieces of stock, whereby waste is eliminated.

In the drawings: Figure 1 is a central longitudinal section through the casing of the spark plug, showing the insulator secured thereto; and Fig. 2 is a perspective view of the two members of the casing detached, and illustrating the manner in which they are cut from the stock.

With my improved method of manufacture, I proceed as follows: A bar of hexagonal stock of suitable dimensions, indicated by dotted lines at A, Fig. 2, is bored, internally threaded and otherwise fashioned to form the member B. This member is

preferably provided with a tapering bore 50 C for fitting against a corresponding surface upon the insulator D, while the large end of this bore is threaded at E to correspond to the threads on the nipple. The nipple is cut from a separate bar of stock, 55 which is of a lesser diameter and round. This is externally threaded at F to correspond to the threads E and is bored at G to provide clearance for the insulator. The two members B and F are then engaged 60 with the insulator D, a suitable packing H being placed between the shoulder I on this insulator and an opposed shoulder J formed by the inner end of the member F. If desired an inner bushing or lining K 65 may be placed between the insulator and the member B, after which the members B and F are relatively rotated to clamp the shoulder I upon the shoulder J.

When the parts are thus assembled, a 70 spark plug is formed which dispenses with the usual threaded bushing, and which is in every way as strong and gas proof.

The nipple is secured into the engine casing by engaging the hexagonal portion 75 with the wrench or other tool, and to prevent relative movement of the members B and F, some locking device, such as a set screw L is used to lock these parts in fixed relation.

80 The cost of the construction is greatly reduced, both by reason of the simplified method of manufacture and the lesser amount of stock which is wasted.

It will be noted that with the construction of plug as described, the insulator is inserted in the metallic casing from the inside and bears against an integral shoulder upon said casing; whereas, in constructions heretofore used the insulator is inserted 90 from the outer end of the casing and requires an additional bushing or clamping device for securing in position.

What I claim as my invention is:

95 A spark plug casing comprising a continuously threaded nipple portion adapted to engage an engine casing, and a polygonal portion, formed of separate members hav-

ing a threaded engagement with each other, said polygonal portion forming the head for said nipple portion, a locking means to prevent relative movement of said members, and an insulator clamped between said members.

In testimony whereof I affix my signature in presence of two witnesses.

ALBERT SCHMIDT.
